(57) **CLAIM**

The ornamental design for a skin cancer screening device, as shown and described.

DESCRIPTION

FIG. 1 is a left front top perspective view of the skin cancer screening device showing our new design;

FIG. 2 is a right back bottom perspective view of the skin cancer screening device;

FIG. 3 is a front view of the skin cancer screening device showing additional detail;

FIG. 4 is a back view of the skin cancer screening device showing additional detail;

FIG. 5 is a left side view of skin cancer screening device showing additional detail;

FIG. 6 is a right side view of the skin cancer screening device showing additional detail;

FIG. 7 is a top view of the skin cancer screening device showing additional detail; and,

FIG. 8 is a bottom view of the skin cancer screening device showing additional detail.

The identifier “dermID” forming part of the claimed design is a registered trademark, the assignee having rights to the trademark.
